JOHN WILLIAM STRAUGHAN, OF PRATT, WEST VIRGINIA, ASSIGNOR OF ONE-THIRD
TO JAMES WALTER MORGAN AND ONE-THIRD TO LOUIS ALBERT CASCI, BOTH OF
PRATT, WEST VIRGINIA.

SWITCH-STAND.

1,099,627.

Specification of Letters Patent.

Patented June 9, 1914.

Application filed January 27, 1914. Serial No. 814,755.

To all whom it may concern:

Be it known that I, JOHN W. STRAUGHAN, a citizen of the United States, residing at Pratt, in the county of Kanawha and State 5 of West Virginia, have invented a new and useful Switch-Stand, of which the following is a specification.

The present invention appertains to switch stands, and aims to provide a novel and improved contrivance of that character.

It is the object of the present invention to provide a switch stand embodying a unique locking mechanism for holding the switch points at one of a plurality of positions, and 15 whereby the switch points may not be thrown by malicious or unwarranted persons.

Another object of the present invention is to provide a switch stand of the nature indicated, which may be readily and conveniently manipulated by the switchman or 20 brakeman, and which may be quickly and effectively locked.

It is also within the spirit of the present invention, to provide a device of the character 25 specified, which will be comparatively simple, compact, durable and inexpensive in construction, as well as being simple, convenient, practical and efficient in its use.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

40 The invention has been illustrated in its preferred embodiment in the accompanying drawing, wherein:—

Figure 1 is a plan view of the switch stand, the upper portion of the shaft being 45 broken away. Fig. 2 is a side elevation of the appliance in open position. Fig. 3 is a sectional view taken on the line 3—3 of Fig. 1. Fig. 4 is an enlarged sectional detail taken on the line 4—4 of Fig. 1. Fig. 5 50 is a sectional view of the handle, on an enlarged scale, and illustrating the key-controlled lock.

In carrying out the present invention, there is provided a base 1, which is adapted 55 to be spiked or otherwise secured upon the

extended ends of the ties T of the rails R, the base 1 being of D-shape and comprising the body or straight portion 2, and the curved or arcuate portion 3. The body portion 2 of the base is provided with a bearing 4 intermediate its ends, and about which the portion 3 is curved as a center, the upright shaft 5 being journaled through the bearing 4 and carrying the usual signals at its upper end. The lower end of the shaft 5 is operatively connected with the switch points, and to this end, an eccentric 6 is secured to the lower end of the shaft 5, below the base 1, and to the eccentric strap 7, is connected a link or connecting rod 8, which is in turn 70 connected with the bar 9, to which the switch points are attached, one of the switch points being designated at 10 in the drawings.

As a means for actuating and locking the shaft 5, a radial arm or lever 11 is keyed 75 or otherwise secured to the shaft 5 so as to seat upon the bearing 4, the free end of the arm or lever 11 moving snugly upon an upstanding arcuate rib 12 provided upon the curved portion 3 of the base 1. At the 80 ends of the rib 12 are stops or lugs 13 for limiting the oscillatory or swinging movements of the arm or lever 11 when the switch points are thrown to either of their two positions respectively.

The arm or lever 11 is provided with a longitudinal slot 14, and with upstanding pairs of ears 15 and 16 at the outer and inner ends of the slot 14, and at the sides of the slot or the sides of the arm or lever 11. A bell crank or angular lever 17 has its elbow fulcrumed between the outer pair of ears 15, by means of a pivot or fulcrum pin 18 engaged through the ears 15 and the elbow of the lever 17, the lower or depending arm 19 of the lever 17 forming a latch engageable with notches 20 provided in the inner edge of the curved portion 3 of the base adjoining the stops 13. The arm 19 of the lever 17 is adapted to swing upwardly 90 through the slot or opening 14, and the said arm or latch 19 is engageable with the notches 20 when the shaft 5 is so swung as to move the switch points to their opposite positions, as will be obvious. The other or 95 upper arm 21 of the lever 17 forms the handle of the lever or arm 11, and is provided adjoining its free end, with upper laterally projecting ears or lugs 22 adapted to seat upon the ears 16 of the arm or lever 11, when 100 105 110

the lever 17 is swung downwardly into engagement with the base 1 of the switch stand. The arm 21 of the locking lever 17 is equipped with a hand hold 23 at its free end for convenience in manipulating the device.

A lifting leaf spring 24 is secured upon the arm or lever 11 and projects between the ears 16, to raise the lever 17 slightly, when the said lever is freed or released from the arm or lever 11. The arm or handle 21 of the lever 17 is hollow, or in the form of a case, and houses a key-controlled lock 25, including the latches or catches 26 adapted to be projected through and retracted within the sides of the arm or handle 21, into and out of engagement with inner sockets or keepers 27 formed upon the ears 16. The latches have a separating spring 26^a between them to project the latches.

The key-hole 28 for the lock 25 is preferably formed in the top of the arm or handle 21, whereby ready access may be had to the lock 25, by the proper key, a pivoted cap or cover 29 for the key-hole 28 being mounted upon the arm or handle 21 for normally closing the key-hole, which is desirable. As clearly illustrated in Figs. 2 and 4, the cap or face plate of the lock 25 may be disposed at the bottom of the arm or handle 21, so as to be shielded or protected, when the arm or handle 21 is swung upon the arm or lever 11.

In practice, the connecting rod or thrust member 8 for the switch points is so connected to the lower end of the shaft 5, that when the arm or lever 11 is swung to the ends of its respective strokes, the switch points will be moved to their opposite positions, as usual. When the lever 17 is free, the same may be swung upwardly, as seen in Fig. 2, for convenience in swinging or oscillating the arm or lever 11, to correspondingly oscillate the shaft 5 for throwing the switch points back and forth. The free end of the arm or lever 11 rides upon the raised rib 12, to reduce friction, and to brace the arm or lever 11 against depression. When the arm or lever 11 is swung against either of the stops 13, the lever 17 may be swung downwardly, as seen in Fig. 3, so that the latch 19 thereof engages the corresponding notch or recess 20 of the base, and in order that the latches 26 of the lock 25 may be snapped into engagement with the sockets 27 of the keeper ears 16 by the spring 26^a. Thus, the arm or lever 11 is locked in place, whereby it cannot be swung by malicious or unwarranted persons, without the employment of the proper key for opening the lock 25 to retract the latches 26 from the keeper ears 16, to enable the lever 17 to be thrown upwardly out of engagement from the base 1. Ordinarily, when switching, the lock 25 may be left open, the spring 24 normally

supporting the lever 17, slightly above its locking position, whereby the lever may be readily raised without the necessity of unlocking the latches 26. Then, when the switch points are finally set, the lever 17 may be depressed against the tension of the spring 24, to lock the lever 17 to the ears 16, as above intimated. When the latches 26 are released from the ears 16, the spring 24 will immediately lift or raise the lever 17, so that the latches 26 will not immediately re-engage the ears 16 as soon as the key is withdrawn from the lock 25.

Particular attention is directed to the fact that the handle or arm 21 is arranged to swing inwardly upon the arm or lever 11, when the switch stand is locked, and that the latch arm 19 is adapted to swing downwardly within the base or the switch stand, which provides a suitable and efficient arrangement.

In view of the foregoing, taken in connection with the drawings, the several advantages and capabilities of the present switch stand will be obvious to those versed in the art, and further comment is deemed unnecessary.

Having thus described the invention, what is claimed as new is:

1. A switch stand including a base, an oscillatory actuating lever mounted thereon, a handle pivoted to the free end of the lever and arranged to swing inwardly upon the same, interengageable means carried by the handle and base and adapted to interlock when the handle is swung upon the lever, and locking means for securing the handle to the lever.

2. A switch stand embodying a base, an actuating lever mounted for oscillatory movements thereon, a handle pivoted to the lever and arranged to swing inwardly upon the same, the handle having a latch, and the base having portions to be engaged by the latch when the handle is swung upon the lever, and locking means for holding the handle against the lever.

3. A switch stand embodying a base having a curved portion provided with inner notches, an oscillatory actuating lever mounted upon the base and having its free end movable upon said curved portion, a handle pivoted to the lever and having a depending latch arm engageable with the notches of the said curved portion of the base when the handle is swung against the lever, and locking means for securing the handle in place against the lever.

4. A switch stand embodying a base having an arcuate portion, the arcuate portion having an upstanding arcuate rib and stops at the ends of the rib, and the said arcuate portion of the base having inner notches adjoining the stops, an oscillatory actuating arm mounted upon the base and having its

- free end movable upon the said rib to swing between the said stops, a handle pivoted to the free end of the arm and having an angular latch arm engageable into the said notches when the handle is swung against the said arm and when the arm is swung against the respective stops, and locking means for securing the handle in place against the lever.
- 19 5. A switch stand embodying a base, an oscillatory actuating arm mounted thereon, a handle pivoted to the arm and arranged to swing thereagainst, interengageable means carried by the handle and base and arranged to interlock when the handle is swung against the arm, a key-controlled lock for locking the handle against the arm, and yieldable lifting means disposed between the arm and handle for swinging the handle away from the arm, when released.
6. A switch stand embodying a base, an oscillatory actuating lever mounted thereon, a handle pivoted to the free portion of the lever and arranged to swing against the lever, the handle having a latch arm, and the base having means for receiving the latch arm when the handle is swung against the lever, a key-controlled lock for locking the handle against the lever, and yieldable lifting means disposed between the lever and handle for lifting the handle from the lever when the handle is released.
7. In a switch stand, a base, an oscillatory actuating lever mounted thereon and having a longitudinal slot and upstanding pairs of ears at the outer and inner ends of the slot, an angular lever having its elbow fulcrumed between the outer pair of ears, one arm of the angular lever constituting a latch arranged to swing through the said slot, the base having means for receiving the said latch when the other arm of the angular lever is swung against the actuating lever, the inner ears of the actuating lever being arranged to receive the second mentioned arm of the angular lever when it is swung against the actuating lever, the second mentioned arm of the angular lever constituting a handle, and a key-controlled lock carried by said handle and including means for engaging the said inner ears.
- In testimony that I claim the foregoing as my own, I have hereto affixed my signature in the presence of two witnesses.
- JOHN WILLIAM STRAUGHAN.
